UNITED STATES PATENT OFFICE

JAMES C. HOBBS, OF PAINESVILLE, OHIO

FURNACE

Application filed September 21, 1925, Serial No. 57,498. Renewed December 3, 1929.

My present invention relates to improvements in furnaces, particularly furnaces in which the combustion chamber is cooled by a circulating medium, and will be best understood from the following description and the annexed drawings, in which Fig. 1 is a sectional side elevation of a steam boiler and its furnace which I have chosen for purposes of illustration of my invention; Fig. 2 is an enlarged view of a portion of the side wall in Fig. 1; Fig. 3 is a section on the line 3—3 of Fig. 2, and Fig. 4 is a view similar to Fig. 3 but showing a modification.

Like reference characters indicate like parts in the several views.

In the illustrative form, a furnace chamber 10 is provided with a front wall 11, a rear wall 12 and side walls 13, the fuel entering the furnace chamber through a powdered fuel burner 14 being projected downward and the burner gases passing from thence upward across the water tubes 15 of the steam boiler illustrated as being used in connection with my novel furnace.

Extending across the furnace chamber is a row of slag-screen tubes 16 of a known form connected at their lower ends to a header 17 and at their upper ends to a header 18. From the header 18 extends upwardly a row of tubes 19 disposed in the rear wall 12 in the manner to be described more in detail hereinafter, the upper ends of the tubes 19 connecting to inclined headers 20, the upper ends of which are connected through pipes 21 and tubes 22 with the steam and water drum 23. The header 17 is connected by pipes 24 and tubes 25 with the drum 23. The arrangement just described provides a water circulation through the tubes 16 and upwardly through the tubes 19.

In the illustrative embodiment, an upper header 26 and a lower header 27 are connected at their opposite ends by downcomers 28 and 29 located outside of the wall 13 and by bent tubes 30 arranged in the side wall in a manner to be described more in detail herein-after. The lower header 27 is connected by a pipe 31 with the pipe 24 and the upper end of the upper header 26 is connected by a pipe 32 and tubes 33 with the steam and water

drum 23. By this arrangement a local circulation is maintained in the side wall cooling tubes 30 by water received from and returning to the drum 23. This tube arrangement, however, is no part of my present invention and the side wall cooling tubes 30 may also be connected in any other suitable manner with a source of cooling water.

The tube arrangement in each of the side walls 13 as well as in the rear wall 12, in the illustrative embodiment, is substantially the same, and a description of one of these walls will be sufficient.

In Figs. 2 and 3 is shown a vertical and a horizontal section of a portion of one of the side walls 13, in which the tubes 30 are bent so as to project inward through the wall from the headers 26 and 27 and then downward parallel to the face of the wall and preferably adjacent the front face of the wall but inside of such face. In the illustrative form, the wall above and below the ends of the tubes 30 is made up of the ordinary masonry refractory with a space at the upper part where the upper end of the tube 30 passes through the wall to permit the tube 30 and the connecting downcomers 28 and 29 to expand without destroying the wall.

The furnace wall is made up of a plurality of fixed channels 34 extending horizontally, the space between the channels being filled by the usual closures 35. Connected to the fixed members 34 is a plurality of spaced vertical I-beams 36. Preferably I make the wall through which the tubes 30 pass, of a plurality of courses of special tile, arranged preferably not only so as to provide grooves or recesses for the tubes 30, but also so that the tile may be held from inward movement while permitting free expansion thereof horizontally and vertically. In the arrangement shown in Figs. 2 and 3, the courses are made up of pairs of tile 37 and 38, 37^a and 38^a, etc., arranged so that the adjacent faces of each pair are behind a tube 30, this space being widened out to provide the recess or groove for the tube. Preferably in laying up the wall, I also provide an open space between the adjacent faces of each pair of tile in each course, as, for instance, between tile 37^a and 38^a.

38, so as to permit expansion of each tile without contacting with the adjacent tile.

In the case of the spaces between each pair of tile, as the space between tile 37^a and 38, for example, the fact that radiant heat can pass through such a space will be more or less immaterial, because the heat can be prevented from doing any harm by the layer of insulating material 39. Furthermore, this 10 space will eventually become filled with slag and prevent the radiant heat from passing between the tile. In the case of the space between the tile of each pair, as 37^a and 38^a for example, the passage of heat through the 15 space is obstructed by the tube 30 in front of such space, this tube 30 being an effective means for preventing the passage of radiant heat through the space and to the metallic member at the rear of the space. The tube 20 30 also prevents slag from accumulating in the space, which in a short time would interfere with the action of the expansion joint.

Where tile or brickwork is laid loosely at the sides of a furnace to allow for expansion, 25 the slag will often fill up the spaces between the tile or brickwork in such a way that the wall becomes cemented together into a solid mass and, on cooling, cracks will be formed as the walls shrink. By protecting the joints 30 by means of the tubes 30, the wall can contract after it expands and there will be no danger of cracking the wall.

The specific form for holding the tile in place which I have illustrated, comprises a 35 T-header member 40 having hooked members at each side engaging the flanges of the I-beam 36 freely, so as to slide up and down thereon, the T-head of the member 40 engaging a T-shaped groove 41 in a recess in the 40 outer side of the wall, this recess being formed preferably partly in the adjacent faces of a pair of tile 37, 38. Preferably the groove 41 does not extend substantially below the horizontal center line of the tile, so that as 45 the several courses of tile are built up resting on each other, the members 40 may be arranged in position and slid down into place in the recess 41 before the next course of tile is applied, the bottom of the recess 41 locating the member 40 at approximately the center of the tile.

Preferably I arrange the contacting faces of the tile in the successive courses so that they are non-planer. This is done so that if 55 spaces should open between the tile, the radiant heat would not pass through such space.

It will be observed that the arrangement which I have described produces a wall in which the cooling tubes are sufficiently inside of the interior of the wall so as to efficiently cool such wall, while, at the same time enabling the maintenance of a furnace temperature which is high enough to give a good efficiency. In order to increase this efficiency, 60 I preferably fill the recesses or grooves con-

taining the tubes 30 with a coherent mass 42 of refractory, after the wall is built and the tubes 30 installed. Preferably I use for this purpose ash slag of the same general character that is produced in powdered fuel furnaces. Such ash slag may be put in place in any desired manner, as, for instance, by means of an air gun. The mass will adhere sufficiently to the tube and the adjacent tile to hold itself in place and, at the same time, will not prevent the horizontal relative motion of the tile 37 and 38, if such motion is produced by variations in temperature.

In operation, particularly where ash slag is used for the mass, if the refractory tile 37 and 38 have their front faces worn or burned away, the refractory mass 42 will also be gradually removed until there comes a point where the heat abstracted through the tubes 30 will balance the heat passing into the furnace wall so as to prevent further destruction of the wall. At the same time, the slag deposited on the wall will serve as a further insulator to protect the wall. While, for some purposes, the tubes 30 may be placed in position and their recesses in the wall permitted gradually to fill up with slag, I find it preferable to fill such spaces with slag before beginning operation, so that, first, a greater layer of slag may be interposed between the tubes 30 and the interior of the furnace and, second, to insure a more positive construction than would be had if dependence were placed on the deposition of slag from the furnace.

In Fig. 4, an arrangement is shown in which the wall, instead of being made up of courses of special tile surrounding the tubes 30, is made up of refractory brick, so as to provide recesses for the tubes 30 and the recesses thus formed are filled with a refractory mass 42' which preferably is of ash slag applied in the manner described above. In a wall of this construction, the wall is retained in a vertical position by the tubes 30 on one side and the I-beams 36 on the other.

It will be understood that the arrangements which I have described are merely illustrative and that the embodiment of my invention may be widely varied.

I claim:

1. In a furnace, a combustion chamber having a vertically disposed wall composed in part at least of tile arranged in horizontal courses with open spaces between the tile of a course, metallic holding members in line with some of said spaces and engaging the tile to prevent inward movement of the tile, each space in line with a metallic member being widened at its inner end to form a tube recess, and a cooling tube in said recess to prevent the passage of radiant heat through the space to said metallic member.

2. In a furnace, a combustion chamber having a vertically disposed wall composed in

part at least of tile arranged in horizontal courses with open spaces between the tile of a course, metallic holding members in line with some of said spaces and engaging the tile to prevent inward movement of the tile, each space in line with a metallic member being widened at its inner end to form a tube recess, a cooling tube in said recess to prevent the passage of radiant heat through the space to said metallic member, and a coherent mass of refractory material in each recess between the tube therein and the combustion chamber.

3. In a furnace, a combustion chamber having a vertically disposed wall having courses of tile therein, fixed members outside the tile, said tile having vertical T-shaped recesses in their outer faces open at the top of each course and closed at the bottom, and holding members connected to said fixed members and free to slide vertically thereon and having T-heads in said T-shaped recesses.

4. In a furnace, a combustion chamber having a vertically disposed wall having courses of tile therein, fixed members having vertical flanges outside the tile, at least some of said tile having vertical T-shaped recesses in their outer faces open at the top of each course and closed at the bottom, and holding members engaging said flanges and free to slide vertically thereon and having T-heads in said T-shaped recesses.

5. In a furnace, a combustion chamber having a wall with courses of tile therein, fixed members outside the tile, cooling tubes in recesses in the inner face of the tile, and connecting members between at least some of the tile and said fixed members and arranged to permit movement of the tile in a direction parallel to the cooling tubes while holding the tile against movement at right angles to the plane of the wall.

6. In a furnace, a combustion chamber having a wall with courses of tile therein, fixed beams outside of tile, at least some of said tile being recessed on the side adjacent said beams, cooling tubes in recesses in the inner face of the tile and extending parallel to said beams, and connecting members engaging said beams and the recesses in said tile adjacent the beams and arranged to permit the tile to move parallel to said beams and said tubes while holding the tile against movement at right angles to the plane of the wall.

7. In a furnace, a combustion chamber having a vertically disposed refractory wall with a plurality of grooves in the inner face thereof, an open joint in said wall extending from each groove to the outer face of the wall, a cooling tube in each of said grooves, and a coherent mass of refractory material in each groove between the tube therein and the combustion chamber, said mass of refractory being non-homogenous with the refractory wall.

8. In a furnace, a combustion chamber hav-

ing a vertically disposed refractory wall with a plurality of grooves in the inner face thereof, an open joint in said wall extending from each groove to the outer face of the wall, a cooling tube in each of said grooves, and a coherent mass of ash slag in each groove between the tube therein and the combustion chamber.

9. A furnace wall having at least a portion thereof formed of tile arranged in horizontal courses and provided with vertical recesses having cooling tubes therein, and means other than the tubes for holding said tile against inward movement, while permitting vertical expansion thereof.

10. A furnace wall having at least a portion thereof formed of tile arranged in horizontal courses and provided with vertical recesses having cooling tubes therein, and means other than the tubes for holding said tile against inward or outward movement, while permitting vertical and horizontal expansion thereof.

11. A furnace wall of tile laid in horizontal courses, said wall having vertical expansion joints, cooling tubes between said joints and the furnace in position to protect said joints, a second set of vertical expansion joints alternately placed with respect to the joints of the first mentioned set, said wall being so proportioned that after it becomes cemented together on the furnace side by means of slag, it will part at the joints which are protected by the cooling tubes and will not crack in the body of the wall.
